UNITED STATES PATENT OFFICE.

ZACHARIAH EDWARD BOOTH, OF NEW BEDFORD, MASSACHUSETTS.

SPINNING AND WINDING MACHINE.

1,153,190.

Specification of Letters Patent. Patented Sept. 14, 1915.

Application filed January 19, 1914. Serial No. 812,941.

To all whom it may concern:

Be it known that I, ZACHARIAH EDWARD BOOTH, a citizen of the United States, and a resident of New Bedford, in the county of Bristol and State of Massachusetts, have invented a new and useful Improvement in Spinning and Winding Machines, of which the following is a specification.

My invention relates to spinning and winding machines and its object is to improve and simplify the construction of the same and increase the efficiency and capacity thereof in the manner hereinafter set forth.

One embodiment of my invention is illustrated in the drawings which accompany and form a part of this specification, in which,

Figure 1 is a transverse section through a machine constructed in accordance with the present invention. Fig. 2 is a plan view of the ring which I prefer to use with the device shown in Fig. 1. Fig. 3 is a vertical section of the ring shown in Fig. 2. Figs. 4, 5 and 6 are sectional views showing details of construction of said ring.

In the particular drawings selected for more fully disclosing my invention, a two-tier creel 10, 10 is shown mounted in the usual way in the rails 11, 12, 13, and oppositely arranged is a lower two-tier creel 10', 10' similarly mounted in the rails 11', 12', 13'. It will be understood, however, that the creel may have any desired number of tiers depending on the product desired. The roving passes as usual through the rolls 14, or 14' and then through its respective eye or guide-wire 15 or 15', each of which, in the present instance, is shown attached directly to the frame of the machine, although it may be attached to a thread-board in the usual manner, and thence to the eye 17 or 17' of the traveler-ring 18, 18', respectively, mounted as hereinafter more fully described, in the ring-rail 16 which is actuated by the slider or lifter-rod 22.

Heretofore in machines of this character a single vertically-disposed spindle is employed carrying a bobbin upon which is wound the yarn from a bobbin or set of bobbins in the creel.

By arranging the spindles substantially horizontally in pairs as shown in Fig. 1 and adding a lower creel, the capacity of the machine will be doubled. I do not, however, limit myself to using two sets of spindles,

inasmuch as any desired or convenient number may be employed, as will be obvious to those skilled in the art.

The substantially-horizontal spindles, each of which carries a bobbin 19, 19' may be driven in the usual way by cords passing over the whorls 20, 20' and may be mounted as shown in Fig. 1 in the brackets 21, 21' secured in any suitable manner to the frame.

It will be understood of course that the usual driving mechanism for the spindles and the usual builder-motion device for the slider or lifter rods may be employed, and inasmuch as such mechanism constitutes no part of my invention I have omitted the same to prevent undue complication of the drawings.

While, for the purpose of explaining my invention, I have shown the same applied to a spinning machine of the rotary-ring type, it will be understood it is not limited in use to such spinning machine, but may be employed in any spinning, roving, or winding machine.

While any suitable construction of ring may be employed, I prefer to use the ring illustrated in Figs. 2 to 6, inclusive, consisting as shown of the two ring sections 23, 24 screwed together and forming a preferably V-shaped race-way for the anti-friction bearings 26 herein shown as ball bearings. The stationary ring is secured in any suitable manner to the ring-holder 25 which is set into the ring-rail 19, as shown in Fig. 3. The traveler-ring 18, provided with the eye 17, has its periphery provided with a V-shaped race-way co-operating with the race-way in the stationary ring, so that when anti-friction bearings are placed in said race-way as shown, the traveler-ring may rotate with respect to the stationary ring with a minimum of friction.

It will be understood of course that the ring herein specifically described is capable of general application and is not limited to use with the machine shown in Fig. 1.

It will be further understood that various modifications may be made by those skilled in the art, in said machine and ring, without departing from the principle of my invention.

I claim:

1. In combination, two oppositely-disposed creels, rolls for each creel and a pair of substantially-horizontal spindles, one ar-

ranged below the other and each adapted to receive the yarn from one of said sets of rolls, the axes of said spindles being substantially at right angles to the axes of said creels.

2. In combination, two oppositely-disposed creels, rolls and a pair of substantially-horizontal spindles, one arranged below the other and adapted to receive the 10 yarn from said rolls, the axes of said spindles

being substantially at right angles to the axes of said creels.

In testimony whereof, I have hereunto subscribed my name this 16th day of January 1914.

ZACHARIAH EDWARD BOOTH.

Witnesses:

FRANCES LOUISE CORCORAN BOOTH,
LELAND CLIFTON PEIRCE.

Copies of this patent may be obtained for five cents each, by addressing the "Commissioner of Patents, Washington, D. C."

It is hereby certified that in Letters Patent No. 1,153,190, granted September 14, 1915, upon the application of Zachariah Edward Booth, of New Bedford, Massachusetts, for an improvement in "Spinning and Winding Machines," an error appears in the printed specification requiring correction as follows: Page 1, line 109, claim 1, before the word "rolls" insert the article and words *a set of*; and that the said Letters Patent should be read with this correction therein that the same may conform to the record of the case in the Patent Office.

Signed and sealed this 7th day of December, A. D., 1915.

[SEAL.]

R. F. WHITEHEAD,

Acting Commissioner of Patents.

Cl. 118—10.
